UNITED STATES PATENT OFFICE.

CARL STILL, OF RECKLINGHAUSEN, AND CARL WESSEL, OF BORBECK, NEAR ESSEN,
GERMANY; SAID WESSEL ASSIGNOR TO SAID STILL.

COKE-OVEN PLANT.

1,340,990.

Specification of Letters Patent. Patented May 25, 1920.

Application filed May 8, 1915. Serial No. 26,852.

To all whom it may concern:

Be it known that we, CARL STILL and CARL WESSEL, engineers, subjects of the German Emperor, and residents, respectively, of Bismarckplatz, Recklinghausen, Prussia, Germany, and of Gasstrasse, Borbeck, near Essen, Prussia, Germany, have invented certain new and useful Improvements in Coke-Oven Plants, of which the following is a specification.

Our invention relates to improvements in coke oven plants, and more particularly to the bench which is located at the discharge side of the coking oven and is used for quenching the coke. One of the objects of the improvements is to build the bench at the discharge end of the coking oven in such a way, that the quenched coke can easily be removed and loaded on cars. Another object of the improvements is to provide means for sifting the coke while being moved from the oven to the trucks, so that only high grade coke is loaded on the trucks. With this and other objects in view our invention consists in providing means whereby the mass of coke which is discharged from the oven is advanced as a whole over the bottom of the quenching bench and to the place where it is loaded on trucks or the like, said means being constructed in such a way, that at the same time while thus advancing the coke the small coke or breeze is sifted from the more valuable lumps of coke. In a coking plant in which our improved system is provided it is not necessary to employ a great number of workmen who heretofore have been necessary for sifting the coke and for loading the lumps on trucks.

For the purpose of explaining the invention two examples embodying the same have been shown in the accompanying drawings, in which the same letters of reference have been used in all the views to indicate corresponding parts. In said drawings—

Figure 1, is a vertical longitudinal section of the plant showing the bench where the coke discharged from the coking oven is quenched,

Fig. 2, is a plan view showing the discharge ends of a series of coking ovens and the quenching bench located before the said discharge ends,

Fig. 3, is a detail view showing a grate or screen provided on the quenching bench,

Fig. 4, is a cross-section of the grate shown in Fig. 3,

Fig. 5, is a vertical longitudinal section similar to that shown in Fig. 1, and showing a modification of the plant, and

Fig. 6, is a plan view of Fig. 5.

Referring to the example illustrated in Figs. 1 to 4, a plurality of horizontal coking retorts *h* are placed one beside the other. In front of the discharge end of the coking ovens there is a bench *l* where the mass of coke *h* which has been discharged from one of the ovens is quenched. The said bench may be built from masonry, and it is provided along its tail or discharge end with a sloping platform or ramp *v*. The bottom of the quenching bench is formed with a gutter *x* which extends over the whole breadth of the bench, which is slightly inclined from both sides and toward the said gutter. The gutter is covered by perforated plates *y* of sheet metal through which the excess of water is removed which has been used for quenching the mass *h* of coke. Between the ramp *v* and the gutter *x* a grate *r* is provided which extends over the whole length of the bench. The bars of the said grate are disposed in the direction of the travel of the mass of coke being moved from the ovens to the ramp *v* and the car, and they are gradually reduced in breadth, the broader end of the bars being located at the side of the coking oven and the reduced end at the side of the sloping discharging ramp *v*. The bars *s* are spaced at suitable distances apart and disposed parallel to one another, and the slits provided between the same are gradually broadened from the side of the coking ovens to the discharge side of the bench. Preferably the said bars *s* are made from rolled iron bars having a cross-section in the form of a T, the vertical webs of the said bars providing the supporting bodies of the bars and the flanges the coke supporting surface. Preferably the bars *s* are made from iron bars of ordinary T-form, the flanges of the bars being so fashioned, that they are gradually reduced in breadth, for which purpose the part *s'* shown in dotted lines in Fig. 3 is removed.

The slits of the grate are provided by disposing the flanges of the bars at suitable distances from one another, and their height corresponds to the thickness of the flanges of the bars. In the foundation of the bench

supports *f* are embedded at suitable intervals which project beyond the rear end of the bench and carry bearings *e* for a shaft *d* which extends along the whole length of the bench and is provided with a plurality of drums *c* suitable arranged at intervals. The shaft *d* is adapted to be rotated by suitable mechanical means such for example as a motor (not shown). It will be easily understood that the drums *c* could be arranged side by side without intervals or that each series of drums between each pair of bearings *e* could be substituted by a cylindrical body corresponding in length to the distance between the said bearings *e*.

Below the grate *r* a channel *t* having in vertical cross-section the form of a funnel is provided in the quenching bench, which channel extends along the bench and is equipped at its bottom with discharge openings *t'* which are adapted to be closed by hinged gates *t²*. The discharge openings *t'* of the funnel shaped channel communicate with another channel *y* below the said channel *t* at the bottom of which rails *y'* are provided for one or more trucks *z*.

For moving the mass of coke from the ovens toward the discharging ramp *v* a scraping off member *a* is provided the length of which is such, that when acting on a mass of coke discharged from one of the ovens it projects beyond the same at both ends. The said scraper is freely located on the quenching bench and is held in contact therewith by its own weight. To the ends of the scraper *a*, drawing-ropes *b* or chains are secured, the opposite ends of which are adapted to be attached to a pair of drums *c* of the shaft *d*. Along the outer side of the quenching bench rails *m* are provided on which a carriage *w* can be run. The rails *m* are disposed in such a way, that the lower edge of the discharging ramp *v* projects above the truck *w*.

The operation of the plant is as follows: The mass of coke is drawn from one of the coking ovens *h* in the usual way, whereupon it falls on the quenching bench *l*. Thereupon the mass of coke is quenched by water in the usual way, the excess of the water flowing to the gutter *x* by means of which it is withdrawn from the coking bench. The scraper *a* is now placed at the rear of the mass *h* of coke, and the chains or ropes *b* secured thereto are attached to two of the drums *c* so that the ropes are as far as possible perpendicular to the shaft *d*. In rotating the shaft *d* the mass of coke *h* is bodily moved by means of the scraper *a* over the quenching bench and toward the discharging ramp *v*. When discharging and quenching the mass of coke, the greatest part of the small coke or breeze gets to the bottom of the pile of coke, so that it falls through the slits of the grate *r* and into the

channel *t* as the mass of coke is being moved over the said grate. While being moved by the scraper *a* the mass *h* of coke remains in the form of a coherent pile in which the lumps retain their respective positions without tumbling one over the other. When the mass of coke arrives on the sloping ramp *v* it falls into the truck *w* which has been placed in position for receiving the coke. Therefore the coke is mechanically loaded right from the bench on the truck. By constructing the bars *s* of the grate in such a way, that the slits provided between the same gradually increase in breadth in the direction of the movement of the coke, it is impossible for small pieces of coke to be held between the bars. The small pieces of coke which get between the bars are pushed forward along the same by the mass of coke moving over the grate until they arrive at a part of the grate where the breadth of the slits is sufficient to permit them to fall through the same. The small coke which is gathered in the channel *t* is removed from time to time by opening the gates *t²*, whereby the small coke is discharged into the truck *z* and removed thereby. If it is desired to remove a mass of coke which has been drawn from one of the other coking ovens of the battery, the free ends of the ropes *b* are attached to the drums *c* which are opposite to the discharge end of the said oven, whereupon the operation is the same as has been described before.

In the modification of the coking oven shown in Figs. 5 and 6 the grate bars *s* are not straight as shown in Figs. 1 to 4, but are bent in such a way, that one part of the grate is substantially horizontal while the other part lies in an inclined plane. Each bar consists of two sections *r¹* and *r²* disposed at an obtuse angle to each other, the parts *r¹* being disposed substantially in the plane of the bench *l*, and the sections *r²* sloping downward substantially in the same direction as the ramp *v*. If desired the sections *r¹* and *r²* may be made integral with each other, and their flanges are formed in the same way as has been described with reference to Figs. 1 to 3. The bars are mounted on the foundation of the quenching bench *l* and they are supported at their middle by a transverse beam *i* supported by the supports *f* which carry the bearings *e* of the shaft *d*. The free ends of the supports *f* are supported on pillars *g*, as is shown in Figs. 5 and 6.

When the mass of coke is moved by the scraper *a* on the sections *r¹* of the grate the greater part of the small coke or breeze falls through the slits of the grate into the passage *t*. That part of the small coke which may accidentally remain within the mass of coke is removed while the mass is

moving over the grate-bar-sections r^2 . When the coke in the form of a coherent pile gets on the part where the sections r^1 and r^2 meet, it will break up and the 5 heavier lumps thereof will roll down on the sloping portions r^2 at increased speed. Thereby the mass of coke is loosened, so that also those parts of the small coke can fall through the slits of the grate which 10 were held within the coherent pile. Therefore, the small coke is removed from the valuable lumps of coke in a higher degree than in the construction described with reference to Figs. 1 to 4.

15 We claim herein as our invention:

1. In combination, a coke oven system comprising a plurality of ovens, a horizontal and wide stationary storing and quenching bench, common to and adapted 20 to receive coke from all of said ovens, said bench being provided with a channel, a screen over said channel, a downwardly disposed stationary ramp extending longitudinally of the bench, and a scraper for

moving a mass of coke from a selected oven 25 in a coherent pile across the bench, over the screen and toward the ramp aforesaid.

2. In combination, a coke oven system comprising a plurality of ovens, a horizontal and wide stationary storing and quenching bench common to and adapted to receive coke from all said ovens, and provided with a channel, a plurality of bars secured in place to form a screen over said channel, the outer ends of said bars being 30 downwardly inclined, a stationary ramp, formed, in part of said outer ends of the bars, and extending longitudinally of the bench, and means for scraping coke from 35 the bench, over the screen and toward the 40 ramp aforesaid.

In witness whereof we have hereunto set our hands in presence of two witnesses.

CARL STILL.

CARL WESSEL.
